US0D1113091S

(12) **United States Design Patent** (10) **Patent No.:** **US D1,113,091 S**
(45) **Date of Patent:** **** Feb. 17, 2026**

(54) **SHOE**

(71) Applicant: **SHENZHEN STARLINK
NETWORK TECHNOLOGY CO.,
LTD, Shenzhen (CN)**

(72) Inventors: **Jie Huang, Shenzhen (CN); Patricia
Thaina Da Cunha Sander, Shenzhen
(CN)**

(**) Term: **15 Years**

(21) Appl. No.: **29/981,498**

(22) Filed: **Dec. 31, 2024**

(30) **Foreign Application Priority Data**

Jul. 4, 2024 (CN) 202430417660.4

(51) **LOC (15) Cl.** **02-04**

(57) **CLAIM**

The ornamental design for a shoe as shown and described.

DESCRIPTION

FIG. 1 is a perspective view of a shoe showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dash-dash broken lines and the areas within depict portions of the shoe that form no part of the claimed design. The figures include textured portions, which depict a stitched fabric of the claimed design.

1 Claim, 8 Drawing Sheets
